[57] CLAIM

The ornamental design for a molding frame for lenses, as shown.

DESCRIPTION

FIG. 1 is an enlarged perspective view of a molding frame for lenses showing our new design;

FIG. 2 is a top plan view thereof;

FIG. 3 is a bottom plan view thereof;

FIG. 4 is a side elevational view taken along line 4—4 of FIG. 2;

FIG. 5 is an end elevational view thereof;

FIG. 6 is a sectional view taken in the direction of the arrows on line 6—6 of FIG. 3;

FIG. 7 is a sectional view taken in the direction of the arrows on line 7—7 of FIG. 3;

FIG. 8 is a sectional view taken in the direction of the arrows on line 8—8 of FIG. 3.

FIG. 1.

FIG. 2.

FIG. 5.

FIG. 3.

FIG. 6.

FIG. 4.

FIG. 7.

FIG. 8.
